UNITED STATES PATENT OFFICE.

JAMES MCGLINSEY, OF TYRONE, AND WALTER A. TRIMBLE, OF BIRMINGHAM, PENNSYLVANIA.

ONE-RAIL CAR.

1,097,104.

Specification of Letters Patent.

Patented May 19, 1914.

Application filed November 30, 1912. Serial No. 734,387.

To all whom it may concern:

Be it known that we, JAMES MCGLINSEY and WALTER A. TRIMBLE, citizens of the United States, residing, respectively, at Tyrone, in the county of Blair, and Birmingham, in the county of Huntingdon, State of Pennsylvania, have invented certain new and useful Improvements in One-Rail Cars, of which the following is a specification.

10 This invention relates to one rail cars, and the principal object thereof is to simplify and improve the cars of this class.

Another object of our invention is to provide a one rail car designed especially for use on railways for carrying heavy material such as this, rails, frogs, switches, etc., from one point of construction to another, but which may readily be used in any place where there are tracks for the operation of

20 cars, such as mines, stone quarries, shops, etc.

With these and other objects in view the invention consists in certain novel construction, combination and arrangement of parts as is hereinafter more fully described, 25 pointed out in the claim and illustrated in the accompanying drawing in which,

Figure 1 is a top plan view of our device, Fig. 2 a side elevation, and Fig. 3 an end elevation thereof.

30 Referring more particularly to the various figures of the drawing in which like numerals indicate like parts throughout, the preferred embodiment of our device provides a rectangular frame work 1 of hollow tubing having its meeting ends screw threaded and engaged by the alining ends of a T-coupling 2, the free end thereof being screw threaded and engaged by the threaded end of a hollow pipe section 3, said pipe 35 section forming the handle of the device and being provided at its outer end with a knob or ball 4.

Provided at intervals between the sides of the rectangular frame 1, are a plurality 45 of cross bars 5, formed of hollow tubing, and extending therethrough and through perforations in the side member are a plurality of tie rods, said rods being threaded

at their ends and fitted with nuts for tightening the side members against the cross bars and thus securely bracing the frame.

It will be noticed by reference to Fig. 3, that the handle 3, extends upwardly at a considerable angle, and it is held in this position and braced against lateral movement by means of the angular brace member 6. This brace member is formed of a length of tubing flattened at the middle and secured to the handle by means of a rivet or bolt 7, the arms being then bent downwardly and flattened at the ends and bent at an angle to snugly fit against the frame, the ends being held in place by means of the tie rods of the outside cross bars, said tie rods extending through the ends and fitted with nuts, thus rigidly securing the brace member in place.

Near the ends of the side members of the frame 1, and directly opposite one another are secured downwardly extending brackets 70 8, said brackets secured by means of rivets or bolts, and serving as bearings for the axle 9. A wheel 10 provided with flanges 11, and a conically shaped reinforcing member 12 which abuts against one of the bearings 8, is keyed or secured in any desired manner to the axle 9.

75 In operation, the wheels are placed upon one of the rails, of the track, the object to be moved placed upon the frame, and the operator walks along parallel to the rail pushing the car along by means of the handle.

Although we have described the specific construction, combination and arrangement 85 of parts comprising the preferred embodiment of our device, yet it is to be understood that such minor changes may be made in that construction, combination and arrangement, as do not depart from the spirit of 90 the invention and the scope of the appended claim.

Having thus described our invention what we claim as new and desire to secure by Letters Patent is:

95 In a device of the kind described, the com-

bination of a rectangular framework formed of a length of tubing bent to shape, a T-coupling connecting the ends of said tubing, a handle secured in said T-coupling, hollow cross bars interposed between the sides of the frame, the irons extending through said cross bars and securing them to the frame, a brace member secured to said handle and to said framework, brackets secured

to said framework, axles supported by said brackets, and wheels secured to said axles.

In testimony whereof we affix our signatures in presence of two witnesses.

JAMES McGLINSEY.

WALTER A. TRIMBLE.

Witnesses:

N. CHANDLER McCONAHY,

S. C. LUPER.
